ATTORNEY

UNITED STATES PATENT OFFICE.

GEORGE W. BEAN, OF NEW HAVEN, CONNECTICUT.

METAL-PLANING MACHINE.

SPECIFICATION forming part of Letters Patent No. 351,895, dated November 2, 1886.

Application filed September 13, 1886. Serial No. 213,443. (No model.)

To all whom it may concern:

Be it known that I, GEORGE W. BEAN, a resident of the town of New Haven, in the State of Connecticut, have invented new and useful Improvements in Shipping Mechanism for Metal-Planing Machines, of which the following is a specification.

My invention relates to shipping mechanism for metal-planing machines and similar reciprocating devices, and has for its object to provide means for releasing the belt-shifter from the reversing mechanism at the end of its throw, whereby the shifter is made independent of the momentum of the planer-bed or platen after the belts are in position at each reciprocation of the mechanism.

The invention consists in the combination of a disengaging rock-arm with a pair of dogs carried upon the belt-shifter, as hereinafter 20 more fully described and claimed.

In the accompanying drawings, Figure 1 is a plan view of the cross-head end of a planer-frame, showing the driving-pulleys and my improved shipping mechanism. Fig. 2 is a 25 side elevation of the shipping mechanism, and Fig. 3 is an enlarged view in horizontal section of one of the tripping-dogs.

Referring to the drawings, A denotes the bed of a planer of the usual and well-known construction, and b', b², b³, and b⁴ denote the driving-pulleys, arranged upon a common shaft, b⁵, which imparts motion to the planer-table or platen through the usual train of gears. (Not shown.). The inner wheel on one 35 side of the planer is fast to the shaft, while the opposite inner pulley is a loose one, and the outer pulleys are also one fast to the shaft and the opposite one loose, there being one fast and one loose pulley upon each end of the shaft. The belts run upon the pulleys in opposite directions, and a belt-shifter, c, is arranged over the pulleys in suitable bearings in the planer-frame, and carries at each end a belt-guide, d. The belt-guides are adjusted at 40 the proper distances apart to hold the belts respectively upon one tight pulley and the opposite loose pulley, and vice versa. All these parts are well known, and require no further description.

50 A pair of collars or parts, n, are fastened upon the belt-shifter c by set-screws or similar

devices, which permit the adjustment of the parts as required. To each of the parts is pivoted a tripping-dog, e, and both dogs are set to trip toward each other, but are prevented from tripping outward or away from each other by abutting at their outer ends against their respective holders n, as shown in Fig. 3. A spring, f, is arranged to act between the dog and holder, and adapted to sustain the dog in its normal position—bearing against the holder n, as described.

Upon one of the cross-beams of the planer-frame is pivoted a rock-arm, g, which is vibrated by the action of the planer-dogs i at 65 each reciprocation of the planer-table by means of the ordinary connecting-rod, h, and rock-shaft k, provided with the exterior and interior arms, l l'. The rock-arm carries an adjustable bar or arm, p, which is extended to 70 just enter between the tripping-dogs when the belt-shifter is midway of its movement. In operation, as the shifter is moved slightly in either direction from its central position, the bar p, which moves in an arc, disengages from 75 the tripping-dogs, which move in a right line, and therefore recede from the bar in proportion to their distance from the central position. As soon as the rock-arm is disengaged from the dogs the movement of the belt-shifter 80 ceases, though the planer-table may be moved somewhat farther by its momentum before it is brought to rest by the action of the oppositely-moving belt. When the table is again reversed, the bar on the rock-arm swings past 85 and tips the nearest tripping-dog, and thus enters between them and engages the opposite dog to shift the movement of the planer-table in a reverse direction. This operation is repeated at each successive reciprocation of the 90 planer-table.

The dogs can be adjusted on the shaft by means of the set-screws by which they are fastened, and the bar p may be adjusted on the rock-arm to give any required throw to the 95 belt-shifter or to compensate for wear. By means of this device the planer may be shipped in much shorter space than with the ordinary shipping devices, and the belt-shifter cannot be carried beyond its proper position in either 100 direction by the momentum of the planer-table. It is evident that this shipping mech-

anism may be used on planers provided with friction-clutches, for which it forms a superior shipping device.

I claim as new and desire to secure by Letters Patent—

1. In shipping mechanism for metal-planing machines, the combination, with a vibrating rock-arm pivoted on the planer-frame and actuated by the movement of the planer-dogs, of a pair of tripping-dogs secured upon the belt-shifter and having rectilinear movement, whereby they are released from engagement with the rock-arm at certain positions in the path of the point of the arm and disengaged from the action of the planer-bed, as and for the purpose specified.

2. In combination, the belt-shifter *c*, supported in bearings in the planer-bed and adapted to traverse in a rectilinear path, the

tripping-dogs *e*, pivoted in their respective 20 holders *n*, secured upon the belt-shifter, the rock-arm *g*, pivoted on the planer-frame and carrying an adjustable arm or extension adapted to engage the tripping-dogs, and means for vibrating the rock-arm by the motion of the planer-bed, substantially as specified.

3. In combination, the belt-shifter *c*, the tripping-dogs *e*, the holders *n*, the springs *f*, the rock-arm *g*, carrying the arm or extension 30 *p*, the connecting-rod *h*, the rock-shaft *k*, the rock-arms *l l'*, and the planer-dogs *i*, all combined substantially in the manner and for the purpose specified.

GEO. W. BEAN.
